UNITED STATES PATENT OFFICE.

ARVID SALOMAA, OF DULUTH, MINNESOTA.

NAIL-HOLDER FOR HAMMERS.

1,379,838.

Specification of Letters Patent. Patented May 31, 1921.

Application filed July 26, 1920. Serial No. 399,148.

To all whom it may concern:

Be it known that I, ARVID SALOMAA, a citizen of the United States, residing in the city of Duluth and State of Minnesota, have 5 invented new and useful Improvements in Nail-Holders for Hammers, of which the following is a specification, reference being had to the accompanying drawings.

This invention is in the nature of a nail 10 holding attachment for hammers, and the object is to provide a very simple and efficient attachment for any hammer, and which when in place will afford a handy clip or holder for the nail while the latter 15 is being started or set in the work.

In the drawings:

Figure 1 is a side elevation of a hammer and attachment.

Fig. 2 is a frontal elevation.

20 Fig. 3 is a rear elevation.

Fig. 4 is a detail of the device itself.

The invention consists of two jaws 3, pivotally connected at 5 and carrying the complementary nail holding notches 7. A 25 U-shaped clamp spring 6 is connected at its base 9 with the pivoted ends of the jaws 3, while the free ends 10 of the spring impinge the outer faces of the jaws 3, thus holding them in contact. Laterally extended curved

spring fingers or grips 2 extend from the 30 pivoted ends of the jaws 3 and engage the handle 1 of the hammer 11, in such manner that the notches 7 become positioned immediately at the side of the hammer 11. The notches 7 engage the head 12 of the 35 nail 8, thus holding the nail in convenient position for starting in the work. The attachment may be readily applied to or taken off any hammer, as desired.

While I have herein described a certain 40 specific method of constructing and assembling the elements of my invention, it is understood same may be varied in minor details, not departing from the spirit of my invention as defined in the appended claim. 45

What I claim to be new and patentable is:

A nail holding attachment for hammers, comprising two jaws pivotally connected at their inner ends and having complementary nail engaging notches in their outer ends; a 50 U-shaped spring mounted over said jaws and adapted to hold them closed; laterally extended grips adapted to releasably engage the hammer handle.

ARVID SALOMAA.
